UNITED STATES PATENT OFFICE

FRANK E. BESSLER, OF AKRON, OHIO, ASSIGNOR TO THE BESSLER DISAPPEARING STAIRWAY COMPANY, OF AKRON, OHIO, A CORPORATION OF OHIO

MOVABLE STAIRWAY

Application filed February 13, 1928. Serial No. 253,811.

My invention relates to movable stairways and particularly to stairways of the disappearing type which are used to provide temporary access to attics or upper floors of buildings not frequently entered. This type of stairway ordinarily includes a hinged panel and a stairway which is mounted for reciprocation longitudinally of said panel.

The main objects of this invention are to provide a steel stairway of the type above referred to which is adapted for concrete or other buildings usually classed as fireproof; to provide counterbalancing tension devices which will be suitable for a steel stairway and panel and which will afford proper balance for these parts; to provide two separate tensioning devices, one tension device for counterbalancing the weight of the panel and another distinct and separate tension device for counterbalancing the stairway; to provide means permitting separate adjustment of the tension of either the panel or stairway counterbalancing device without affecting the tension of the counterbalancing device of the other part; to provide an arrangement of parts which will permit the selection of one strength of tension device for the panel and a different strength of tension device for the stairway; to provide a compact arrangement of the tension devices so as to effect economy of space; to provide an improved method of mounting the tension devices so as to produce a rigid construction; to so mount the tension devices as to facilitate assembling and removal for inspection or repairs; to provide two independent tension devices on each side of the stairway, all tension devices being mounted on separate supports and one pair of said tension devices being connected to the panel and the second pair of said tension devices being connected to the stairway, thus to enable any one of the four tension devices to be removed without the other; and to provide improved rolling supports, guides and stops for a steel disappearing stairway.

Further objects and advantages of this invention will appear from the following description and claims, considered in connection with the accompanying drawings.

The annexed drawings and the following

description set forth in detail certain means embodying my invention, said disclosed means, however, constituting but one of the forms in which the principle of my invention may be applied.

55

In said annexed drawings:

Figure 1 is a vertical sectional view of a disappearing stairway and panel embodying my invention and showing the stairway and panel in the lowered position, this view being 60 taken in the planes indicated by the line 1—1, Figure 2;

Figure 2 is a top plan view of the parts shown in Figure 1;

Figure 3 is a view similar to Figure 1 but 65 showing the panel in the up position and the stairway in the up and concealed position, this view being taken substantially from the planes indicated by line 3—3, Figure 4;

Figure 4 is a top plan view of the parts 70 shown in Figure 3;

Figure 5 is an enlarged view of a portion of Figure 4, this view being confined to showing the counterbalancing tension devices and other parts associated therewith on one side 75 of the stairway, the upper side as shown in Figure 4;

Figure 6 is a side elevation of the parts shown in Figure 5, this view being taken from the plane indicated by line 6—6, Figure 80 5;

Figure 7 is a cross-sectional view taken in the planes indicated by line 7—7, Figures 3 and 6;

Figure 8 is a cross-sectional view through 85 one of the counterbalancing tension devices, the view being taken in the plane indicated by line 8—8, Figure 6;

Figure 9 is a longitudinal sectional view through one of the counterbalancing tension 90 devices showing the method of mounting the springs therein;

Figure 10 is a fragmentary plan sectional view through the axis of one of the drums, this view being taken in the plane indicated 95 by line 10—10, Figure 8;

Figure 11 is a fragmentary side elevational view of a portion of one of the plates of the assembly illustrated in Figures 5 and 6;

Figure 12 is a detached view of one of the 100

end plates used in connection with the mounting of the counterbalancing tension devices;

Figure 13 is a section taken in the plane indicated by line 13—13, Figure 6, this view showing an elevation of the adjustable hinge for supporting the panel;

Figure 14 is an enlarged view of a portion of Figure 1, showing the upper rolling support, guides and stops for the steel stairway;

Figure 15 is a plan view taken from the planes indicated by the inclined line 15—15, Figure 14;

Figure 16 is a fragmentary sectional view looking upward, taken in the plane indicated by the line 16—16, Figure 14;

Figure 17 is an enlarged view of a portion of Figure 1, showing the lower rolling support and guides for the steel stairway; and

Figure 18 is a fragmentary sectional view looking upward, taken in the plane indicated by the line 18—18, Figure 17.

Referring to the annexed drawings in which the same parts are indicated by the same respective numerals in the several views, a ceiling 1 of a room is provided with a suitable opening 2, leading to the attic, this opening having a frame 3 consisting of upper and lower metal angles 4, and plates 5 and side plates 6. In contact with one of the end plates 5 adjacent the side plates 6 are mounted two hanger plates 7 which are provided with flanges 8 at their upper ends, said flanges being secured to an upper angle 4 by means of screws 9, as clearly shown in Figures 5 and 6. These hanger plates are provided with flanges 10 near their lower ends in which are suspended two screws 11, Figures 6 and 13. These screws have threaded engagement with a hinge 12 which is guided in recess 13 formed in the lower end of the hanger plate 7. The hinges 12 constitute a hinged support for one end of the panel 15. The opposite end of this panel is supported by means to be hereinafter described. These screws 11 are used for purposes of adjustment in erection, primarily so as to provide means for varying the distance from the hinge pin 14 to the flange 8 at the top of the hanger plate 7 to accommodate possible variations in thickness of the ceiling 1. This provision of adjustment is necessary because it is essential that the lower face of the panel 15 should be flush with the ceiling 1. It is to be understood that the screws 11 are to be used for adjusting the height of the hinges during erection and that, after the hinges have been properly located, they are secured to the end plate 5 of the frame 3 by means of screws 16 as clearly shown in Figures 6 and 13.

A longitudinally-extending plate 17 for supporting one side of certain tension devices is mounted in contact with each of the side

plates 6 and is secured to the same by means of screws 18 at one end and is provided with a flange 19 at the other end, which flange, in turn, is riveted to the hanger plate 7. Similarly riveted to the opposite end of the hanger plate 7 is a flange 21 of a second plate 20, for supporting the second side of the tension devices, which plate 20 is formed with a right angle wall 20^a, Figure 5, this wall also being provided with a flange which is riveted to plate 17 and is secured to the longitudinal plate 6 of the frame 3 by means of the screws 18. It will be seen that the supporting plates 17 and 20 together with hanger plate 7 form a box support and enclosure for the counterbalancing tension devices, which, in the specific form exemplified in the drawings, consist of spring-controlled drums 22 and 23. Each plate 17 and 20 is formed with a pair of raised portions which in turn are provided with slots 24 semi-circular at their lower ends except for tongues 25 which are formed integrally with the plates 17 and 20 and which project upwardly into the slots 24.

All drums 22 and 23 and their supporting means are of similar construction and it will therefore be necessary to describe only one of them.

Each drum 22 and 23 is mounted on a hollow axle 26. The length of this axle is equal to the distance between the outside faces of the plates 17 and 20 when assembled, as shown in Figure 5.

Each drum is likewise provided with side flanges 27 and with a cylindrical body portion 28, Figure 7, this cylindrical portion 28 being formed of a single plate rolled to cylindrical shape. This plate is provided with tongues extending through slots in the flanges 27, these tongues being slightly riveted over to rigidly secure the parts of the drum together. The cylindrical portion 28 is so formed that a small open space or slot 29, Figure 9, remains between the abutting ends of this cylindrical portion. A flat spiral spring 30 has one end provided with a hook 31 which is adapted to fit into the slot 29 and the other end of said spring is similarly provided with a hook 32 which projects into a slot 33 in the axle 26. Each of the side flanges 27 of the drum is provided with a hub 34 rotatably mounted on the axle 26. A recess 35 is formed in each end of the axle 26. This recess, it will be understood, is cut through both walls of the axle in a direction at right angles to the axis. The width of the recess is the same as the width of the tongue 25 in plates 17 and 20. The depth of each recess is preferably equal to the thickness of one of the plates 17 or 20 plus the thickness of one of certain similar end plates 36. These end plates 36 are adapted to slide over the ends of the axle 26 and have two segmental openings 37 to permit the plate to slide over the projecting portions of the axle and these end

plates are also formed with a bar 38 of the same width as the tongue 25 of plates 17 and 20 which bar is adapted to slide into the recess 35 in the end of the axle. One of these plates 36 is mounted upon each end of the axle 26 and the two plates are thereafter screwed or otherwise secured against displacement by means of the screw or other fastening means 39. It will be understood that the bars 38 limit the inward movement of the end plates 36 by striking against the bottom of the recess 35, and it will also be understood that the bottoms of the recesses are spaced from the ends of the axle 26 a distance slightly greater than the over-all width of the hubs 34 on the drums 22 and 23, in order that the drums may be free to rotate. It will be understood that each assembly consisting of a drum 22 or 23, axle 26, end plates 36 and screw 39, forms a unit and can easily be handled without coming apart. It will be noted that the axle projects beyond the end plate 36 on each end an amount equal to the thickness of the side plates 17 and 20.

This assembled drum unit is adapted to be lowered into place by sliding the projecting ends of the axle 26 into the slots 24 and causing the recesses 35 to register with the tongues 25 in the plates 17 and 20. After being thus located the end plates 36 are secured to the plates 17 and 20 by means of screws 40 for which suitable holes are tapped in the end plates 36 and provided in the support plates 17 and 20. It will also be noted that these screws are located above the level of the top of the ceiling which is normally the attic floor level. This arrangement provides easy access to the screws 40, thus permitting the drum units to be readily and quickly removed for inspection or repairs. An additional spacing member 41 is provided to suitably space the plates 17 and 20. A flange 42 on the supporting plate 17 is suitably secured to one of the angles 4 of the frame 3 to assist in transmitting the load to the frame 3.

As stated above, one of these sets of drums is mounted at each side of the opening 2 adjacent the side plate member 17. A round bar 43 extends from the plate 20 on one side of the opening to the corresponding plate 20 on the other side of the opening. This bar is suitably secured to the plates 20 and thus serves as a spacing member to properly space the two support plate units. This bar 43 serves as an axle for two rollers 44 which are rotatably mounted on said bar and which serve as rolling supports for the stairway, as will be hereinafter described.

Two steel cables or other flexible members 45 are secured to the drums 22 in any suitable manner and lead from the top of these drums to pulleys 46 mounted in brackets 47, which, in turn, are supported on the frame 3, as clearly shown in Figures 1 to 4 inclusive. To the opposite end of each of these cables is se-

cured a bracket 48 rotatably supporting a grooved pulley 49. This pulley is adapted to run on the round equalizing bar 50 which, in turn, is connected by means of two brackets 51 with the panel 15. It will thus be seen that the lowering of the panel from the position shown in Figure 3 to that shown in Figure 1, which can be conveniently done by pulling on the hand-chain 52, will cause the spring 30 inside of the drum 22 to wind up and therefore increase its tension. Likewise, it will be seen that the tension of this spring 30 will cause the panel 15 to rise to the closed position shown in Figure 3 as soon as the tension of the spring is greater than the weight of the panel and its superimposed load. It will also be noted that a lug or stop 53, which is made in two halves and is adjustably clamped on each of the cables 45, Figures 1 and 2, serves to stop the panel 15 in the desired lowered position by striking against the ear 54 on the bracket 47. It should likewise be noted that the grooved pulley 49 travels from the right-hand position shown in Figure 1 to the left-hand position shown in Figure 3 as the panel 15 is lifted toward the ceiling, which will be clearly evident from the drawings and which need not be further referred to here as it forms the subject matter of another patent application.

Suitably secured to the drums 23 are two steel cables or other flexible members 55 which run from the bottom of these drums. The other ends of these cables are anchored by means of brackets 56 to the steel stairway 57. This steel stairway consists of treads 58 supported on angles 69, hand-rail 59, suitable bracing 60 and two angle stringers 61, as shown in Figures 1 to 4, Figure 7 and Figures 14 to 18. As shown, these angle stringers are arranged with one flange horizontal and the other flange vertical. Mounted on the panel 15 are two brackets 62, each of which supports a roller 63. These rollers, together with the rollers 44 previously referred to, support the stringer angles 61, these rollers 63 and 44 being properly spaced laterally so that the horizontal flanges of the stringer angles 61 will run on top of the rollers, and the vertical flanges of the stringer angles will serve as lateral guides.

Special guides are provided to guide the stairway and to prevent the stairway stringers from jumping off the rolling supporting wheels 44 and 63, which will now be described.

As shown in Figures 14, 15 and 16, the wheels 44 are mounted on shaft 43. Inside of and adjacent to each wheel 44 is mounted a pivoted guide bracket 64, which is pivotally mounted on shaft 43, and the upper end of which is substantially the same diameter as the wheel 44. These brackets are connected by a bar 65 which is provided with a right angle bend at each end and is secured to each

5 pivoted guide bracket 64 by a rivet 65^a. This bar 65 is provided so that the pivoted guide brackets 64 are rigidly held a definite distance apart, which distance is slightly less than the dimension between the toes of the two stringer angles 61 of the steel stairway. These pivoted guide brackets 64 are further held in their correct position, laterally, by shoulders 43^a formed on the shaft 43. One 10 face of the hub of the wheels 44 is in contact with a pivoted guide bracket 64 and the other face of the hub is held in position by means of the split cotter pin 66, mounted in the shaft 43, this arrangement insuring the 15 proper location of the wheels 44 on the shaft 43.

20 Each wheel 44 supports the horizontal flange of one of the stringer angles 61 and this stringer angle is thereby prevented from moving downward. In order to prevent the stringer angle from jumping upward, the pivoted guide bracket 64 is provided with a flange 67 at the top which projects outwardly over the horizontal flange of the 25 stringer angle 61, thus preventing the stringer angle from jumping upward. It will be understood that this flange 67 normally has sliding engagement with the horizontal flange of the stringer angle 61. Below 30 the flange 67 is provided the flange 68 of an angle which is riveted to the pivoted guide bracket 64 by means of the rivets 65^a and 64^a. This angle is so located that its flange 68 will be in sliding engagement with the underside 35 of the stringer angle 61. The flanges 67 and 68 thus serve as a guide in which the horizontal flange of the stringer angle 61 slides.

40 Referring to Figure 14, the upper tread 58^a is supported by two angles 69^a, only one of which is shown in this figure. These angles 69^a are connected by bolts 70 and 71 to the stringer angles 61 and longitudinal member 72 of the stairway. Riveted to these angles 69^a by means of rivets 69^b is a stop 45 angle 73 which is provided with projecting flanges 74. These flanges 74 move up and down with the stairway and thus move away from and toward the pivoted guide brackets 64 as the stairway is raised or lowered. It will 50 be noted that the flanges 67 on the pivoted guide brackets 64 intersect the path of movement of the flanges 74 and that, therefore, the flanges 67 act as a stop to the downward movement of the flanges 74 and thus fix the 55 lowermost position (see Figure 1) of the stairway, as is clearly shown in Figures 14 and 16.

60 In order to assemble this stairway, it is necessary to remove the upper tread 58^a and its angles 69^a by disconnecting the bolts 70 and 71. The stringer angles may then be threaded between the flanges 67 and 68 and thereafter the upper tread 58^a and its supporting angles 69^a and their attached parts 65 may be replaced. In order to facilitate the

threading of the horizontal flange of the stringer angle 61 between the flanges 67 and 68, the flange 68 is made slightly longer than the flange 67, as is shown in Figure 14.

70 Referring now to Figures 17 and 18, it will be noted that the horizontal flanges of the stringer angles 61 ride on the rollers 63 which in turn are supported in the brackets 62. One side of the hub of each of these rollers 63 75 contacts with a bracket 62 and the other side is in contact with a cotter pin 75, the roller being thus guided laterally and definitely fixed with relation to the bracket 62 which, in turn, is riveted to the panel 15. Pivotally mounted on a pin 76 at the upper end 80 of the bracket 62 is an angle member 77 provided with a flange 78. This flange 78 projects above the horizontal flange of the stringer angle 61, as is clearly shown in Figure 18. The roller 63 prevents the stringer 85 angle 61 from moving downward with relation to the panel 15 and the horizontal flange 68 prevents the stringer angle from accidentally jumping off this roller 63. This flanged angle 77 is pivoted so that the flange 90 78 will not bind on the horizontal flange of the stringer angle 61 as the stairway assumes slightly different angles in the raising and lowering.

95 The extension of the stairway on the panel from the position shown in Figure 3 to that shown in Figure 1 will cause the springs 30 inside of the drums 23 to wind up and thus increase their tension, and thus increase the pull of the drums when the stairway is in its 100 nearest approach to the vertical position at which time it exerts its greatest pull on the cables 55—55. It will be understood that the strength of the tension of the springs 30 in the drums 23 will be so selected that this 105 tension will practically counterbalance the weight of the stairway in its different positions so that the stairway can be reciprocated on the rollers 63 and 44 by the operator with slight physical effort, the weight of the stair 110 structure when extended slightly overcoming the counterbalancing force so that the stairway will retain its position of use until retracted.

115 It will be evident that it is possible to separately adjust the tension exerted by any one of the four drums by removing the assembled drum unit from its seat in the support plates 17 and 20, rotating the drum one-half revolution, one revolution, or as many more revolutions as may be necessary and replacing the drum. The rotation of the drum will cause the spring to be put under a greater or less tension depending upon the direction in which the drum is rotated. It will also be evident 120 that the axle 26 is locked against rotation due to its engagement with the bars 38 on end plates 36 and tongues 25 on plates 17 and 20. For reasons of economy in the use of material, the support plates 17 and 20 are made 125 130

of as thin material as possible and still insure sufficient strength. The thickness of this material is ordinarily not sufficient to insure satisfactory resistance to the greater intensity of the stress transmitted by the axle 26 to these plates when the springs 30 are under heavy tension. The addition of the plate 36 with its bar 38 provides the extra thickness required to properly support the axle and secure it against rotation. Inasmuch as these plates 36 and 17 and 20 are usually made of the same thickness of material, it will be evident that the bearing of the shaft 26 in its support has twice the area 15 with little additional expense for metal. The provision of the end plates 36 and their attachment to the support plates 17 and 20 will, also, prevent the spreading of these support plates at the axle.

20 In the construction of stairways of this type, it is always desirable to keep the opening 2 as small as possible for a given width of stairway, not only to save as much attic floor space as possible but also for reasons of economy in construction. It will be seen that the amount of space occupied by the counter-balancing drums in a lateral direction is not greater than the width of a single drum due to the tandem arrangement of the two drums 25 on each side.

30 Stairways of this general type have been made of wood for many years. However, the building of a stairway of steel involves many different problems than the construction of 35 a wood stairway of this type, due to the different shapes of the materials used in the construction and also due to the heavier weights and other different features involved in this construction, so that successful steel 40 stairways of the type described herein have been developed only after a long and careful series of experiments.

The operation of this apparatus is very simple. Assuming that the stairway is in the 45 lowered position shown in Figure 1, it is only necessary for the operator to slide the stairway 57 upwardly and to the right with relation to the panel 15, as shown in Figure 1, until the lower end of the stairway is in line 50 with the lower end of the panel 15. This operation of sliding the stairway upwardly is made easy due to the pull of the drums 23 as explained above. This will automatically remove sufficient weight from the panel 15 so 55 that the tension of the spring 30 in the drums 22 will cause the panel with the retracted stairway to assume the upper position shown in Figure 3. It will be understood that the panel remains in this position until the operator again pulls the hand-chain 52. When 60 the operator pulls this hand-chain in order to lower the stairway, the steps outlined above take place in reversed order. It will be understood that the panel 15 will stop in the 65 desired lowermost position as determined by

the location of the stops 53 on the cables 45 and that the stairway will stop in the desired lowermost position as determined by the flanges 74 striking against the flanges 67. These last-named stops are so located that 70 the upper tread 58^a of the stairway will be level with the attic floor.

Having thus described my invention, what I do claim and desire to secure by Letters Patent is:

1. A movable stairway comprising, in combination with a ceiling-opening metal frame formed with upper and lower peripheral angle members, and end plates and side plates secured to and connecting said angle members; a pair of spaced hanger plates secured to one of said angle members adjacent one of said end plates; hinges vertically adjustably mounted upon said hanger plates; a steel panel supported at one end by said 85 hinges; a pair of spaced box supports secured to said hanger plates and said side plates, respectively, each box support comprising vertical side members secured respectively to the ends of said hanger plates at 90 one end and secured to said side plate at the other end, one of said side members being also secured to said upper angle member, one of said side members being formed with a right angle end portion, a pair of longitudinally-spaced vertical open-top slots being 95 formed in each of said side members adjacent said hanger plates, said side members being formed with upwardly-extended tongues 100 projecting into said slots; a pair of axle members formed with end recesses adapted to register with said tongues; end plates secured to said axle members, having web bars also adapted to fit said axle recesses, and secured to said side plates; a pair of drums for 105 each box housing having hub portions rotatably mounted on said axles; coil springs secured at one end to each of said axles and at the other end to the side walls of said drums, respectively; a bar connecting said pair of 110 box supports adjacent said hanger plates; a pair of rollers rotatably mounted on said bar adjacent the ends thereof; a pair of pulleys 115 rotatably mounted on opposite sides of said metal frame adjacent the end thereof opposite to said hanger plates; pulleys movably secured to said panel; cables secured to one of each pair of drums at one end, traversing said first-mentioned pulleys, and connected at their other ends to said second-mentioned 120 pulleys, respectively; a steel stairway; cables secured at one end adjacent the bottom of said stairway and secured at the other end to the other of each pair of drums, respectively; a pair of rollers mounted upon said 125 panel adjacent the lower end thereof, said stairway being longitudinally movable of said panel upon said last-mentioned rollers and also upon said rollers mounted on said bar connecting said box supports; means for 130

guiding said stairway; and means for preventing the latter from jumping off said rollers.

2. A movable stairway comprising, in combination with a ceiling-opening metal frame; a pair of spaced hanger plates secured to and adjacent one end of said frame; hinges vertically adjustably mounted upon said hanger plates; a steel panel supported at one end by said hinges; a pair of spaced box supports secured to said hanger plates and the sides of said frame, respectively; a pair of longitudinally-spaced vertical open-top slots being formed in each of said box supports, the latter being formed with upwardly-extended tongues projecting into said slots; a pair of axle members formed with end recesses adapted to register with said tongues; means for securing said axle members to said box supports; a pair of drums for each box housing having hub portions rotatably mounted on said axles; coil springs secured at one end to each of said axles and at the other end to the side walls of said drums, respectively; a bar connecting said pair of box supports adjacent said hanger plates; a pair of rollers rotatably mounted on said bar adjacent the ends thereof; a pair of pulleys rotatably mounted on opposite sides of said metal frame adjacent the end thereof opposite to said hanger plates; pulleys movably secured to said panel; cables secured to one of each pair of drums at one end, traversing said first-mentioned pulleys, and connected at their other ends to said second-mentioned pulleys, respectively; a steel stairway; cables secured at one end adjacent the bottom of said stairway and secured at the other end to the other of each pair of drums, respectively; rollers mounted upon said panel adjacent the lower end thereof, said stairway being longitudinally movable of said panel upon said last-mentioned rollers and also upon said rollers mounted on said box supports; means for guiding said stairway; and means for preventing the latter from jumping off said rollers.

3. A movable stairway comprising, in combination with a ceiling-opening metal frame; a pair of spaced hanger plates secured to and adjacent one end of said frame; hinges mounted upon said hanger plates; a steel panel supported at one end by said hinges; a pair of spaced box supports secured to said hanger plates and the sides of said frame, respectively; a pair of longitudinally-spaced vertical open-top slots being formed in each of said box supports, the latter being formed with upwardly-extended tongues projecting into said slots; a pair of axle members formed with end recesses adapted to register with said tongues; means for securing said axle members to said box supports; a pair of drums for each box housing having hub por-

tions rotatably mounted on said axles; coil springs secured at one end to each of said axles and at the other end to the side walls of said drums, respectively; rollers rotatably mounted on said box supports; pulleys rotatably mounted on said metal frame adjacent the end thereof opposite to said hanger plates; pulleys movably secured to said panel; cables secured to one of each pair of drums at one end, traversing said first-mentioned pulleys, and connected at their other ends to said second-mentioned pulleys, respectively; a steel stairway; cables secured at one end adjacent the bottom of said stairway and secured at the other end to the other of each pair of drums, respectively; rollers mounted upon said panel adjacent the lower end thereof, said stairway being longitudinally movable of said panel upon said last-mentioned rollers and also upon said rollers mounted on said box supports; means for guiding said stairway; and means for preventing the latter from jumping off said rollers.

4. A movable stairway comprising, in combination with a ceiling-opening metal frame; a pair of spaced hanger plates secured to and adjacent one end of said frame; hinges mounted upon said hanger plates; a steel panel supported at one end by said hinges; two pairs of axle members; means for mounting the latter in said frame with each pair in tandem arrangement; drums having hub portions rotatably mounted on said axles; coil springs secured at one end to each of said axles and at the other end to the side walls of said drums, respectively; rollers rotatably mounted upon said frame; pulleys rotatably mounted upon said frame adjacent the end thereof opposite to said hanger plates; pulleys movably secured to said panel; cables secured to one of each pair of drums at one end, traversing said first-mentioned pulleys, and connected at their other ends to said second-mentioned pulleys, respectively; a steel stairway; cables secured at one end adjacent the bottom of said stairway and secured at the other end to the other of each pair of drums, respectively; rollers mounted upon said panel adjacent the lower end thereof, said stairway being longitudinally movable of said panel upon said last-mentioned rollers and also upon said rollers mounted on said frame; and means for guiding said stairway.

5. A movable stairway comprising, a ceiling support; a panel hingedly mounted thereon; rollers mounted upon said support and rollers mounted upon said panel; a stairway mounted on said rollers and longitudinally movable thereover; two pairs of drums independently removably mounted on said support; cables connecting two of said drums and opposite sides of said panel; cables connecting the other two of said drums and op-

posite sides of said stairway; and spring tension devices adapted to be wound more tightly by the lowering of said panel, the tension of said spring devices being substantially equivalent to the weight of said panel and stairway in the lowermost position of the latter.

6. A movable stairway comprising, a ceiling support; a panel hingedly mounted thereon; rollers mounted upon said support and rollers mounted upon said panel; a stairway mounted on said rollers and longitudinally movable thereover; two pairs of drums mounted in tandem adjacent the two sides of said support; cables connecting one of the drums on each side and opposite sides of said panel; cables connecting the other two of said drums and opposite sides of said stairway; spring tension devices mounted within the first of said pair of drums and adapted to be wound more tightly by the lowering of said panel; and means for independently removing and adjusting and replacing said first pair of drums to secure the desired spring tension.

7. A movable stairway comprising, in combination with a ceiling-opening metal frame; a pair of spaced hanger plates secured to and adjacent one end of said frame; hinges mounted upon said hanger plates; a steel panel supported at one end by said hinges; two pairs of axle members; means for mounting the latter in said frame with each pair in tandem arrangement; drums having hub portions rotatably mounted on said axles; coil springs secured at one end to each of said axles and at the other end to the side walls of said drums, respectively; rollers rotatably mounted upon said frame; pulleys rotatably mounted upon said frame adjacent the end thereof opposite to said hanger plates; pulleys movably secured to said panel; cables secured to one of each pair of drums at one end, traversing said first-mentioned pulleys, and connected at their other ends to said second-mentioned pulleys, respectively; a steel stairway; cables secured at one end adjacent the bottom of said stairway and secured at the other end to the other of each pair of drums, respectively; rollers mounted upon said panel adjacent the lower end thereof, said stairway being longitudinally movable of said panel upon said last-mentioned rollers and also upon said rollers mounted on said box supports; means for guiding said stairway; means for adjustably limiting the amount of panel movement; and means for limiting the amount of stairway movement.

8. A disappearing stairway for a ceiling opening comprising a panel hinged at one end of said opening; a stair structure carried by the panel and extensible and retractile thereon; means comprising a spring drum and cable thereon connected to the panel substantially to counterbalance the panel and the

stairway when retracted; means comprising a spring drum and cable thereon connected to the stair structure substantially to counterbalance the stair structure when the panel is open, said spring drums being located in said ceiling opening adjacent the panel hinges; and means located toward the other end of the opening over which the cable connected to the panel is trained.

9. A disappearing stairway for a ceiling opening comprising a panel hinged at one end of said opening; a stair structure carried by the panel and extensible and retractile thereon; means comprising a spring drum and cable thereon connected to the panel substantially to counterbalance the panel and the stairway when retracted; and means comprising a spring drum and cable thereon connected to the stair structure substantially to counterbalance the stair structure when the panel is open.

10. A disappearing stairway including a ceiling panel adapted to open and close a ceiling opening; a stair structure extensible and retractile on said panel; means for substantially counterbalancing the panel and stair structure when the stair structure is retracted on the panel; and independent means substantially to counterbalance the stair structure when the panel is open.

11. A disappearing stairway for a ceiling opening comprising a panel hinged at said opening to open and close the same; a stair structure carried by and extensible and retractile on the panel; means for substantially counterbalancing the panel and stair structure and adapted slightly to overbalance the same when the stair structure is retracted on the panel so as to normally hold the panel shut, said means being adapted to be overcome by extension of the stair structure when the panel is open; and means for substantially counterbalancing the stair structure when the panel is open, said means being adapted to be slightly overbalanced by the stair structure so as to tend to hold the stair structure extended.

Signed by me this 8th day of February, 1928.
